UNITED STATES PATENT OFFICE.

ELIJAH H. DANFORTH, OF JAMESTOWN, NEW YORK.

SUTURE-CLAMP.

SPECIFICATION forming part of Letters Patent No. 268,632, dated December 5, 1882.

Application filed July 21, 1882. (No model.)

To all whom it may concern:

Be it known that I, ELIJAH H. DANFORTH, of Jamestown, in the county of Chautauqua and State of New York, have invented certain 5 new and useful Improvements in Surgical Instruments for Cleft Palates; and I do hereby declare that the following is a full, clear, and exact description thereof, which will enable others skilled in the art to which it appertains 10 to make and use the same, reference being had to the accompanying drawings, which form a part of this specification.

The object of my invention is to make an efficient surgical clamp for drawing together and holding a cleft palate; and it consists in a clamp or double needle, which will be fully understood by the following specification and accompanying drawings, in which—

Figure 1 shows the invention as applied. 20 Fig. 2 shows socket-needle section. Fig. 3 shows ratchet-needle section. Fig. 4 shows invention in perspective. Fig. 5 shows a modification. Figs. 2, 3, 4, and 5 are enlarged views.

25 Heretofore in attempting to close or unite a cleft palate the two sides or parts have been drawn together by means of one or more bent needles being put through from one part to the other, and then winding a silver thread 30 around and across the needle in form of the figure 8; but this method is found objectionable, because there is no way to increase or diminish the tension or draw of the instrument, and the parts get strangled, and then there is 35 no hope of uniting them. To overcome this objection, and to insure a speedy and permanent cure, I make what I term a "needle-clamp," which consists of the parts as shown in Figs. 2 and 3. Fig. 2 shows the socket-needle, 40 which I generally make of silver, and the socket *b* may be of any desired form to receive the ratchet-needle, Fig. 3. The socket *b* has secured to it a spring-pawl, *d*, the end of which is bent so as to drop into the ratchet *e* when the 45 parts are put together, as shown in Fig. 4, and the parts held at any desired point. I generally make the clamp as shown in Fig. 4, but

do not confine myself rigidly to this form; but the clamp must be in two parts and have a ratchet and spring-pawl or its equivalent for 50 holding the parts at any desired distance.

In the practical operation of the instrument I run one needle-point *a* into one side and the other needle-point *a* into the other side of the parts to be closed, and then bring the needles together, letting the ratchet part pass into the socket, as shown in Figs. 1 and 4, and the end of the spring *d* falling into the ratchet, the parts may be drawn together and held as desired. The edges to be grown together are 60 cut, so that by holding them together they readily heal. Several of these clamps have to be used in order to hold the parts, and the needles can be adjusted so as to draw the parts gradually together, and if at any time 65 found too tight can readily be loosened, and every part favored to make a speedy and permanent cure.

In the modification as shown in Fig. 5 I dispense with needle-points *a a* and flatten 70 one end of each part of the clamp, and securely fasten anchor-points *c c*, and these incline toward the center. They are anchored into the flesh on each side of the part to be healed, and drawn together and held by the spring-pawl and ratchet, as before. This form of clamp 75 is more especially adapted to close gaping wounds; but either form may be used for this purpose.

I claim—
80 A needle-clamp for drawing together and holding cleft palates, gaping wounds, &c., composed of two separate parts, one of which has a ratchet and the other a socket and spring-pawl, each part having a needle or points for 85 entering the flesh, substantially as shown and described, and for the purpose set forth.

In testimony that I claim the foregoing as my own invention I have hereto affixed my signature in presence of two witnesses.

ELIJAH H. DANFORTH.
